UNITED STATES PATENT OFFICE.

WILLIAM R. ROYER, OF WILKES-BARRE, PENNSYLVANIA.

CAP FOR PNEUMATIC-TIRE VALVES.

1,408,959.

Specification of Letters-Patent.

Patented Mar. 7, 1922.

Application filed February 8, 1921. Serial No. 443,416.

To all whom it may concern:

Be it known that I, WILLIAM R. ROYER, a citizen of the United States of America, residing at Wilkes-Barre, in the county of 5 Luzerne and State of Pennsylvania, have invented certain new and useful Improvements in Caps for Pneumatic-Tire Valves, of which the following is a full, clear, and exact description.

10 This invention relates to caps for pneumatic valves, and its chief object, briefly stated, is to provide a cap which will permit inflation or deflation of the tire without removal of the cap, inflation being accomplished merely by pressing the air hose nozzle upon the cap itself. A further object is to provide a cap which, although permitting inflation or deflation without removal, will obviate the necessity of using the customary 15 dust cap. Still another object is to provide for the purpose described a device of simple character which can be manufactured at relatively low cost. To this and other ends the invention consists in the novel features and 20 combinations hereinafter described.

In the preferred form of the invention I provide a member in the form of a tubular nipple, which is at one end threaded internally, so as to be screwed down firmly upon 25 the usual reduced outer end of the valve stem. Secured on the outer end of the nipple in any convenient manner is an open topped cup, and in the latter is a sliding rod which extends through the bottom of the cup 30 into the nipple, and can be depressed to depress the valve plunger of the valve stem. The plunger actuating rod is normally held in vertical position by a helical spring surrounding it, and on its top is pivoted a short 35 arm carrying on its outer end a convex bead or button. Enclosing the cap, and arranged to slide on the neck of the nipple is an inverted cup having at its outer end an air port with which the aforesaid button cooperates as a closure. The spring serves also 40 to hold the button seated in the air port and to hold the cap in raised position. When, however, the cap is depressed against the tension of the spring, the button or closure is 45 cammed out of the air port and the rod is depressed, thereby depressing the valve plunger and opening a path for air into or out of the tire.

The embodiment outlined above is illustrated in the accompanying drawings, in which—

Fig. 1 is a sectional view showing the de-

vice mounted on the valve stem of a pneumatic tire, with the parts in their normal positions, the cap and rod being raised and the air port closed.

Fig. 2 is a sectional view similar to Fig. 1, but showing the cap and rod depressed and the closure cammed out of the air port.

Fig. 3 is a side view showing the cap 65 locked in depressed position for deflation of the tire.

Fig. 4 is a sectional view illustrating a modification of the form shown in Fig. 1.

Fig. 5 is a sectional view of the form 70 illustrated in Fig. 4, but showing the cap and rod in depressed position with the air port open.

The device 10, preferably in the form of a tubular nipple, has its lower end threaded 75 on the inside and when in use is screwed upon the reduced outer end 11 of the valve stem 12, the nipple being seated firmly upon the shoulder 13. If desired, a yielding gasket 14 may be provided between the two 80 for the purpose of making a tight joint to exclude water, dirt, or other foreign matter.

On top of the nipple or device 10 is a cylindrical cup 15 having on its bottom a 85 neck 16 by which it is secured in place. This cup may be made of metal, as are the other parts described, but preferably it is composed of rubber which is yielding but yet rather stiff so as to give the cup a certain amount 90 of rigidity. In the cup 15 is a sliding rod 17 extending into the body of the nipple, so that when the rod is depressed its lower end, which may be enlarged for the purpose, as indicated at 18, will engage the valve plunger 19 and depress the same, thereby opening the valve, as will be readily understood. The head 18 is normally held against the bottom of the yielding neck 16 by the tension spring hereinafter described, so that 100 even if the valve in the stem 12 be defective, air from the tire cannot escape through the neck 16, leakage around the bottom of the nipple being prevented by the gasket 14 already described.

105 The rod 17 is provided with a T-head 20, on which is pivoted a short arm 21 terminating in a convex button 22. A cap 23 having an air port 24 is provided to enclose the cup and the inner rod, the cap being fitted 110 snugly to the cup but adapted to slide vertically thereon. At its bottom the cap has a flange 25 which, in cooperation with a bead or flange 26 on the upper end of the nipple

prevents removal of the cap. The flange 25 may usually be formed by spinning the metal down upon the nipple after the parts are assembled.

5 The rod 17 is held normally in rest position by a coil spring 27, the lower end of which bears on a metal washer 28 in the bottom of the cup. At the top the spring engages the T-head 20 and has its extremity 29 extended into contact with the closure button 22, so that normally the parts will be held in the position illustrated in Fig. 1, that is, with the cap and rod raised and with the closure 22 held yieldingly in the air port.

10 15 It will be observed that the closure 22 is convex and that the edges of the air port 24 are beveled. Consequently, when the cap is depressed the rod 17 will not only be depressed also, but the closure 22 will be cammed out of the air port, the arm 21 rocking on the T-head 20 against the tension of the spring 29. The parts are then in the position shown in Fig. 2 and are caused to assume such position by the pressure of the 20 nozzle on the end of the air hose (not shown), which is in practice applied to the outer end of the cap 23 and pressed down with sufficient force to overcome the tension of the spring. To permit deflation of the 25 tire when desired, without the necessity of holding the cap down, the neck of the nipple 10 is provided with a bayonet stud 30 to cooperate with a bayonet slot 31 in the edge of the cap, so that the cap may be locked in depressed position, as clearly shown in Fig. 3.

30 35 In the modification shown in Figs. 4 and 5, the inner cup 15 (Fig. 1) is omitted, and in lieu of the lower head 18, which when the parts are raised is seated against the bottom 40 of the neck 16, a tapered plug 32 is provided on the rod 17 to cooperate with a tapered seat 33 in the neck of the nipple 10. I also provide on the inside of the cap 15 a shoulder 34 under which may be placed a 45 gasket 35 to cooperate with the upper end of the nipple when the cap is depressed, as in Fig. 5, to open the tire valve.

It is to be understood that the invention is not limited to the specific constructions 50 herein described, but can be embodied in other forms without departure from its spirit.

I claim—

1. In a device for the purpose described, 55 the combination with the valve stem of a pneumatic tire, having a valve plunger, of a member mounted on the valve stem, a rod movable longitudinally in the said member to depress the valve plunger, a depressible 60 cap enclosing the rod and having an air port, an arm pivoted on the rod and having a closure for the air port, and a spring associated with the rod to hold the cap and rod in rest position with the air port closure 65 seated in said port.

2. In a device for the purpose described, the combination with a pneumatic tire valve stem having a valve plunger, of a depressible normally raised cap associated with the valve stem and having an air port, a normally raised plunger-actuating rod enclosed by the cap and depressible therewith, an arm pivoted on the rod and having a closure normally seated in the air port but movable out of the same by depression of the cap, and a spring associated with the rod and arm to hold the same and the cap in normal position.

3. In a device for the purpose described, the combination with a pneumatic tire valve stem having a valve plunger, of a depressible cap associated with the valve stem and having an air port, a rod in the cap and depressible therewith to engage and depress the valve plunger, a spring arranged to hold the rod and cap in raised position, and a closure for the air port, normally held therein by the spring but adapted to be shifted out of the port by depression of the cap.

4. In a device for the purpose described, the combination with a pneumatic tire valve stem having a valve plunger, of a member secured on the stem, a rod movable longitudinally through said member to depress the valve plunger, a depressible cap enclosing the rod and having an air port, a spring associated with the rod to maintain the same yieldingly in raised position, and a closure for the air port, normally held in said port by the spring and adapted to be shifted out of the port by depression of the cap.

5. A device for the purpose described, comprising a nipple adapted to be seated on the end of a valve stem, a rod movable longitudinally through the outer end of the 105 nipple to depress the plunger of the valve stem, a spring normally holding the rod in raised position, a cap slideable on the nipple and enclosing the plunger and spring and having an air port, and a closure for the air 110 port, movably mounted on the rod and adapted to be cammed out of the port to open the same by depression of the cap.

6. A device for the purpose described, comprising a nipple adapted to be seated on the end of a valve stem, a rod movable longitudinally through the outer end of the 115 nipple to depress the plunger of the valve stem, a spring normally holding the rod in raised position, a cap slideable on the nipple and enclosing the rod and spring and having an air port, and a closure for the air port, pivoted on the rod and adapted to be cammed out of the port to open the same by depression of the cap.

In testimony whereof I hereto affix my signature.

WILLIAM R. ROYER.
